UNITED STATES PATENT OFFICE

108,239

DESIGN FOR A PLATFORM SCALE

Claude R. Kirk, River Forest, Ill.

Application December 2, 1937, Serial No. 73,319

Term of patent 14 years

To all whom it may concern:

Be it known that I, Claude R. Kirk, a citizen of the United States and a resident of River Forest, county of Cook, and State of Illinois, have invented a new, original, and ornamental Design for a Platform Scale, of which the following is a specification, reference being had to the accompanying drawing, forming a part thereof.

In the drawing, Fig. 1 is a front perspective

view of a platform scale showing my new design with the signs or symbols appearing in Fig. 2 omitted. Fig. 2 is an enlarged elevational view of the upper part thereof.

I claim:

The ornamental design for a platform scale, as shown.

CLAUDE R. KIRK.
